UNITED STATES PATENT OFFICE.

LORA E. POOLE, OF ANDERSON, INDIANA, ASSIGNEE, BY MESNE ASSIGNMENTS, TO DELCO-REMY CORPORATION, OF DAYTON, OHIO, A CORPORATION OF DELAWARE.

ARMATURE-ASSEMBLING APPARATUS.

Application filed June 28, 1926. Serial No. 118,875.

This invention relates to apparatus for assembling armature and dynamo-electric machines, and particularly for assembling hair-pin bar conductors upon a slotted core.

5 It is among the objects of this invention to provide certain improvements in this type of apparatus which will facilitate the assembling operation and therefore reduce the cost of this part of manufacturing of the dynamo-electric machines.

Further objects and advantages of the present invention will be apparent from the following description, reference being had to the accompanying drawings, wherein a 15 preferred form of embodiment of the present invention is clearly shown.

In the drawings:

Figs. 1 and 2 are longitudinal sectional views of the armature holding apparatus, 20 Fig. 1 showing the ends of the hair-pin conductors introduced into the slots of the armature core, and Fig. 2 showing the armature conductors in final position;

Fig. 3 is a plan view of the armature core 25 shown in Fig. 1;

Fig. 4 is a plan view of the core holder shown in Figs. 1 and 2;

Fig. 5 is a front elevation of an armature assembling machine including the work-holder shown in Figs. 1 and 2, the work-holder, the armature core, and work-holder support being shown in section; and

Fig. 6 is a side view, partly in section, of the machine shown in Fig. 5.

35 Referring to the drawings, 20 designates the base supported by legs 21. The base 20 supports a frame 22 carrying a cylinder 23 within which a piston 24 is slidable. Piston 24 is connected with a vertically movable rod 25 provided with a groove 26 in the sides thereof for receiving an armature shaft 27. The shaft 27 is assembled with a laminated slotted core 28 having slots 29 which are lined with S-shaped core lining members 30 40 providing channels 31 and 32 adapted respectively to receive the outer branches 33 and the inner branches 34 of the hair pin bar conductors 35. While but two of these bar

conductors 35 are shown in all figures of the drawing except Fig. 4, it will be understood 50 that each slot 29 receives the branches of two different bar conductors. It is apparent that each slot lining member 30 includes two loops joined by an intermediate portion 30^a. The upper end of the core 28, as viewed in Figs. 55 1 and 2, is insulated by a non-conducting disk 36 of slightly greater diameter than the metal disk of the core. The disk 36 is provided with closed slots 37 through which the lining members 30 extend. The lower end of the 60 core 28 is insulated by a non-conducting disk 38 of slightly smaller diameter than the metal plates of the core and is provided with slots spaced similarly to and located in radial alinement with the core slots. The lining 65 members 30 extend also through the disk 38.

The work holder or armature support is a cup-shaped member, designated in its entirety by numeral 40, which includes an outer tubular member 41 with the thin-walled 70 tubular member 42 and a cylindrical member 43. These members are press-fitted together so as to form a cup member having an end wall provided by the cylinder member 43 for supporting the armature core. The 75 tubular member 41 is provided on its interior with a plurality of equi-angularly-spaced, longitudinally extending ribs 44 which define grooves 45 for receiving the outer branches 33 of the hair-pin conductors. 80 These ribs 44 extend from the bottom of the member 41 to the elevation of the surface 46 upon which the core 28 rests. The member 41 is provided interiorly with a plurality of equi-angularly-spaced, longitudinally extending ribs 47 which are located in alinement with the grooves 45 and extend above the surface 46. Each rib 47 is adapted to enter a core slot 29 when the core is inserted with the cup member 40. These ribs 47 85 serve to prevent lateral movement of the lining members 30 and also aline the slots of the core with the conductor-receiving apertures of the cup members.

The conductor-receiving apertures provided by the cup members for receiving the

inner branches 34 of the hair-pin conductors 35 are provided by grooves 50 which are defined by equi-angularly-spaced, longitudinally extending ribs 51 extending from the periphery of the inner member 43. The angular spacing of the ribs 51 corresponds with the angular spacing of the ribs 44, and the member 43 is located with respect to the member 41 so that the ribs 51 and 44 are in radial alinement. As shown in Figs. 1 and 2, the ribs 51 extend below the surface 46. The intermediate member 42 is a section of thin-walled metal tubing which is press-fitted between the members 41 and 43, and which provides means for partitioning the grooves 45 and 50 so that the outer row of conductor bar branches 33 will be separated from the inner row of branches 34. The intermediate member 42 also provides means for preventing endwise movement of slot lining members 30 while the conductors 35 are being moved endwise relative to the core. It will be noted that the upper edge of member 42 is located vertically below the intermediate portions 30^a of slot lining members and therefore provides an obstruction to the vertical downward movement of these members. The upper edges of ribs 44 and 51 are beveled at 44^a and 51^a respectively in order to facilitate the entrance of the hair-pin conductor branches into the grooves 45 and 50.

The inner member 43 of the work holder 40 is provided with a central aperture 57 for receiving the shaft 27, the lower end of which extends below the extension 58 of member 43. The extension 58 is provided with an aperture transverse the aperture 57 for receiving a pin 59 which is press-fitted into position and is provided with an aperture in alinement with the aperture 57 to permit the shaft 27 to extend through the pin 59. The ends of the pin 59 which project sidewise from the extension of member 43 provide trunnions for the work holder 40 which is pivotally supported by the base 20. It will be noted that the axis of the pin 59 is at right angles with, and intersects the axes of the work holder 40 and rod 25.

The work holder or cup member 40 is moved to the dotted line position 40^a shown in Fig. 6 when loading or unloading the work. Before the armature core and shaft assembly is inserted in the cup member 40 the required number of hair-pin conductors 55 are introduced into or nested in the core slot as indicated in Fig. 1. An apertured disk 70 is placed around the shaft 27, the yoke portion 35^a of the conductors being received by annular groove 71 provided in the disk 70. Then this assemblage of the shaft, core, bar conductor and disk 70 is placed in the cup member when in the position 40^a, the lower end of the core resting upon the surface 46. Then the cup member 40 is tilted 60 into full line position shown in Fig. 5 by

pushing against the shaft 27 until the shaft engages the bottom of groove 26 of the rod 25. Then a pressure fluid is admitted to the cylinder 23 above the piston 24 in any well known manner, thereby causing the rod 25 to move downwardly into engagement with the disk 70 in order to move said disk and the conductor 35 from the position shown in Figs. 1 and 5 to the position shown in Figs. 2 and 6. During the movement of the conductors relative to the core the outer branches 35 of the conductor will be received by the grooves or apertures 45 and the inner branches 34 will be received by the grooves or apertures 50 which have been provided by cup member 40, as previously explained. Since the conductor branches fit snugly within the channels 31 and 32 provided by the slot member 30 these members tend to move downwardly with the conductor branches. Due to the obstruction provided by the intermediate ring member 42 endwise movement of the slot lining members 30 is prevented.

After the assembling operation has been performed, a pressure fluid is admitted to the lower end of the cylinder 23 below the piston 24 while the pressure fluid above the piston is vented. The rod 25 will be moved upwardly to the position shown in Fig. 5. Then the operator may grasp the shaft 27 and move the cup member 40 and parts held thereby into the dotted line position indicated by numerals 27^a, 70^a, 23^a, and 40^a in Fig. 6. The assembled work may then be removed and work to be assembled inserted within the cup member 40.

In order to dislodge the armature assembly from the work holder, in case it should not come out readily by pulling shaft 27, there is provided a work ejector which comprises a rod 80 located below the base 20 and oblique to the rod 25. The rod 80 is movable through the base into engagement with the lower end of the shaft 27. The rod 80 is connected with the piston 81 movable in a cylinder 82 attached by bracket 83 to the base 20. A pressure fluid may be admitted to the cylinder 82 below the piston 81 through a pipe 84 in order to move the rod 80 upwardly. A spring 85 may be used to restore the piston 81 to the position shown after the admission of pressure fluid ceases and the space between the piston and the bottom of the cylinder 82 is vented.

While the form of embodiment of the present invention as herein disclosed, constitutes a preferred form, it is to be understood that other forms might be adopted, all coming within the scope of the claims which follow.

What is claimed is as follows:

1. Armature assembling apparatus comprising, in combination, a cup-shaped member having a cylindrical recess for receiving

- a slotted armature core, each slot having non-conducting lining means for receiving the branches of hair-pin conductors the ends of which have been introduced into the slots, 5 the end wall of the member having apertures for receiving the conductor branches and means for preventing movement of the slot lining means; and means for moving the conductors endwise relative to the core. 79
- 10 2. Apparatus according to claim 1, and provided with means pivotally supporting the cup-shaped member so that the armature may be moved into and out of alinement with the conductor moving means. 75
- 15 3. Armature assembling apparatus comprising, in combination, a member for supporting an end of a slotted armature core assembled upon a shaft, each core slot having non-conducting lining means for receiving the branches of hair-pin conductors the ends of which have been introduced into the slots, the core-supporting wall of said member having an aperture for receiving the shaft, apertures for receiving the conductor branches and means for preventing movement of the slot lining means; and means for moving the conductors endwise relative to the core. 80
- 20 4. Apparatus according to claim 3, in which the conductor moving means includes an apertured disk adapted to be placed around the shaft and against the yoke portions of the hair-pin conductors, and a movable rod engageable with the disk and provided with a recess for receiving the shaft. 85
- 25 5. Armature assembling apparatus comprising, in combination, a cup-shaped member having a cylindrical recess for receiving an open slotted armature core, each slot having non-conducting lining means for receiving the branches of hair-pin conductors the ends of which have been introduced into the slots, the cylindrical side wall being provided with ribs adapted to enter the slots to retain the insulation means, the end wall having apertures for receiving the conductor branches and means for preventing movement of the slot lining means; and means for moving the conductors endwise relative to the core. 100
- 30 6. Apparatus according to claim 5, in which means are provided for dislodging the core from the cup-shaped member. 105
- 35 7. Armature assembling apparatus comprising, in combination a cup-shaped member having a cylindrical recess for receiving an open slotted armature core assembled with a shaft each slot having non-conducting lining means for receiving the branches of hairpin conductors the ends of which have been introduced into the slots, the cylindrical side wall being provided with ribs adapted to enter the slots to retain the insulation means, the end wall having apertures for receiving the shaft and the conductor 110
- 40 branches, and means for preventing movement of the slot lining means; and means movable axially of the shaft for engaging the conductor yoke portions in order to move the conductors relative to the core. 115
- 45 8. Apparatus according to claim 7, in which the cup-member is pivotally mounted so that the core may be moved into and out of alinement with the conductor moving means. 120
- 50 9. Apparatus according to claim 7, in which means engageable with the shaft is provided for moving the core in order to dislodge the core from the cup-shaped member. 125
- 55 10. Apparatus according to claim 7, in which the cup-member is pivotally mounted so that the core may be moved into and out of alinement with the conductor moving means and in which a movable rod is provided for engaging an end of the shaft in order to dislodge the core from the cup-member, the shaft being moved into alinement with said rod when the core is moved out of alinement with the conductor moving means. 130
- 60 11. Armature assembling apparatus comprising in combination, a base, a fluid-pressure cylinder supported above the base; a piston within the cylinder; a rod attached to the cylinder and vertically movable between the base and cylinder; a cup-shaped member located below the rod and pivotally supported by the base and rotatable about an axis at right angles to and intersecting the axis of the rod and the axis of said member, and adapted to receive a slotted armature core assembled upon a shaft, each slot of the core containing non-conducting lining means adapted to receive the branches of hair-pin conductors which have been inserted in the slots, the cup-shaped member having an end wall supporting the core and provided with apertures for receiving the shaft and conductor branches, and having means for preventing movement of the lining; means engageable with the conductor yokes and adapted to receive pressure from the rod in order to move the conductors relative to the core. 135
- 65 12. Apparatus according to claim 11, and provided with a rod located below the base and oblique to the first-mentioned rod, and movable through the base in engagement with the lower end of the shaft when the cup member is tilted out of alinement with the first-mentioned rod. 140
- 70 13. A cup-shaped member for supporting a slotted armature core provided with slot lining members adapted to receive conductor bars, comprising in combination, inner, outer and intermediate, closely-fitting, cylindrical members; the outer member being tubular and provided internally with equi-angularly-spaced, longitudinally extending ribs 145

defining grooves for receiving the outer conductor bar ends; the inner member being cylindrical and provided externally with ribs disposed and spaced similarly to and located in radial alignment with the ribs of the outer member and for the purpose of defining grooves for receiving the inner conductor bar ends; and the intermediate mem-

ber being a thin-walled tube spacing the radially aligned ribs of the inner and outer members and separating the conductor receiving grooves provided between the ribs of said inner and outer members.

In testimony whereof I hereto affix my signature.

LORA E. POOLE
